UNITED STATES PATENT OFFICE.

MAX A. G. LUEDTKE, OF WEEHAWKEN, NEW JERSEY, AND HUGO HOFFMANN, OF NEW YORK, N. Y.

MARKING, PRINTING, AND EMBOSSED DEVICE.

Application filed December 21, 1925. Serial No. 76,595.

This invention relates to marking, printing and embossing devices.

An object of the invention is to provide an improved apparatus for branding, embossing, or applying plain or lustrous letters, ornamental designs, monograms, or legends on articles made of leather, leather substitutes, fibre, paper, woven textile fabrics, and other materials, which apparatus shall comprise few and simple parts, shall be compact in construction, relatively cheap to manufacture, easy and simple to manipulate, and practical and efficient in operation to a high degree.

Other objects of this invention will in part be obvious and in part hereinafter pointed out.

The invention accordingly consists in the features of construction, combinations of elements, and arrangement of parts, which will be exemplified in the construction hereinafter described, and of which the scope of application will be indicated in the following claims.

In the accompanying drawing, in which is shown one of the various possible illustrative embodiments of this invention,

Fig. 1 is a plan view of a machine embodying the invention;

Fig. 2 is a front elevational view taken at a section on line 2-2 in Fig. 1 showing the frame in its raised position;

Fig. 3 is a rear elevational view of the machine showing the frame in its lowered position;

Fig. 4 is a cross-sectional view taken on line 4-4 in Fig. 1 showing the construction of the type disc mounting;

Fig. 4^a is a fragmentary cross-sectional view showing the disposition of the parts with the discs in raised position;

Figs. 5 and 6 are cross-sectional views taken on lines 5-5 and 6-6 respectively in Fig. 4;

Fig. 7 is a cross-sectional view taken on line 7-7 in Fig. 3;

Figs. 8 and 9 are fragmentary elevational and plan views respectively showing a modified border type parts being shown in section to illustrate the assembly of the elements;

Fig. 10 is a fragmentary plan view of another modified form of border type; and

Fig. 11 is a perspective view of a frag-

mentary portion of the discs, showing the interchangeable type element in position.

Referring in detail to the drawing, the apparatus 10, embodying the invention there shown, is particularly adapted for applying identification initials, monograms, designs, or the like to sweat bands, bags, brief cases, and for like purposes, and is seen to comprise an elongated bed or base 11 having spaced stanchions 12 upstanding at one end thereof, the other end of said base being provided with a raised surface or platen 13 on which the article or material is rested during the operation of branding, embossing, or printing, as will hereinafter be described.

A frame 14 is pivotally mounted to swing on a shaft 15 which is fixedly supported between the upper ends 12^a of said stanchions. To retain the frame in a normally raised position, the pivoted or rear end thereof may be made fork-shaped to accommodate a suitable coil spring 16 wound on the shaft 15 between the forked portions 14^a of said end of the frame. The spring 16 is suitably fixed to the shaft 15, preferably at its mid-portion 16^a, as by screw 17, with the free ends 16^b thereof extending to the underside of said forked portions 14^a, as shown in Fig. 1.

The spring 16 is set to urge the ends 16^b against the forked portions 14^a for normally retaining the frame 14 in a raised position, and for automatically returning said frame to the normal position after being depressed.

Suitable detent means is provided such as stop 17^a, projecting from one of the fork portions 14^a, said stop being adapted to engage the adjacent stanchion 12 for limiting the upward swing of the frame 14, as shown in Figs. 1 and 2.

The free end of the frame 14 may be constructed with spaced forwardly extending bracket arms 14^b between which a pair of bracing members 14^c are disposed. A shaft 18 is rigidly carried to extend transversely of the length of the frame by said arms and members, the members being joined together by a cross bar 14^e from which there forwardly extends a handle 19 for swingably depressing the frame.

Mounted for rotation on the shaft 18 between the bracing members 14^c may be one or more discs, comprising set of three in the

form shown in the drawing, and consisting of a center disc C, a right disc R, and a left disc L. These discs are adjustably mounted on the shaft 18 for movement with respect to each other, and each of them carries on the peripheral surface thereof, in uniform spaced relation, suitable die or type elements 20, such as letters of the alphabet, numerals, or other indicia, from which may be set up and formed a wide and varied range of desirable combinations of initials, designs, monograms, or legends to be applied to the material or article.

The discs are arranged to be releasably interlocked so as to move as a unit when the type elements are set in a desired combination. For this purpose, the center disc C is mounted to revolve against the collar 21 fixed to the shaft 18, said disc C being provided with one or more pins 22 having the ends 22R and 22L extending outwardly from either side of the disc C and adapted to engage in holes 23R and 23L provided in concentric rows and uniformly spaced on the sides of the discs R and L facing the pin ends 22R and 22L respectively, one hole being provided to correspond to each type element carried on the periphery of each disc. The mountings for said discs R and L comprise axially extending hollow shafts 24R and 24L respectively, which are slidably and rotatively supported on the shaft 18. The discs R and L are secured respectively to one end of the hollow shafts 24R and 24L, and said shafts have suitable knobs 25R and 25L fastened at the other ends thereof to facilitate setting said discs, as will hereinafter appear. Suitable springs 26R and 26L are provided between the bracket arms 14^b and the knob ends of the hollow shafts 24R and 24L respectively for normally retaining the discs C, R and L set so as to interlock and abut each other. (See Figs. 4 and 5).

The type elements 20 carried on the peripheral surfaces of each disc may comprise the twenty-six letters of the alphabet uniformly spaced from each other, and there may also be provided a grooved space c, r, and l in each disc C, L and R respectively, for receiving an interchangeable type element 20^a, as shown in Figs. 4 and 11.

The type elements may be aligned and set in a desired combination, substantially in the plane of the frame 14 as at V (see Figs. 2 and 3), just above the handle 19, so that the operator has unobstructed view of the aligned type elements during the setting operation.

With the apparatus 10 having three discs, as shown in Figs. 1 and 4, a desired combination of type letters, as, for example, ABA may be set up and aligned as follows: The knob 25L is first pulled out of its normal position and to the left against the action of spring 26L, thus sliding the hollow shaft 24L and the disc L to disengage the pin ends 22L from the holes 23L in the disc L. The discs

C and R are now free from the disc L and, by means of the knob 25L, may be rotated together until the desired type letter, as, for example, B, on the disc C, appears at V. Before returning the knob 25L to its normal position, it is rotated until another desired type letter, such as A, aligns with the said letter B. On releasing the knob 25L, the spring 26L forces the disc L back to its normal abutting position against the disc C, the pin ends 22L re-engaging in the disc holes 23L, thus interlocking discs C and L in the desired combination. The knob 25R is now pulled against the action of the spring 26R thus sliding the hollow shaft 24R and the disc R to the right, out of their normal abutting position against the disc C, to disengage the pin ends 22R from the disc holes 23R. The disc R is rotated, free from the other discs, until the third desired type letter, such as A, appears at V, in alignment with the type letters already set, completing the sequence of type letters forming the desired combination. On releasing the knob 25R, the spring 26R returns the disc R to its normal abutting position against the disc C, and the pins 22R, re-engage in the disc holes 23R thus interlocking the discs to form a unit.

To bring the desired combination of aligned type letters, ABA, from their set position at V, as shown in Fig. 2, to brand, emboss, or print the article or material M, resting on the raised surface 13 of the base 12, suitable means is provided for rotating said discs as a unit into effective contacting position with said material M, as shown in Figs. 3 and 4. Said means is preferably incorporated in the construction of the apparatus 10 to automatically operate, on depressing the handle 19, and is seen, from Figs. 1, 2 and 4, to comprise a plate 27, secured to rotate with the hollow shaft 24L, said plate being spaced in parallel alignment with the disc L, and having a concentric row of uniformly spaced perforations 27^a, corresponding in number to the holes in the disc L. A pin 28 releasably engages in one of said holes for controlling the movement of the interlocked discs as a unit. Said pin may be supported to oscillate in a slot 29^b formed in a depending arm 29^a of a cross-head 29, the latter being reciprocatingly mounted on an overhanging slideway 30^a which is rigidly secured to the frame 14 so as to extend over said plate. The pin 28 connects with one end of a link 32, the other end of said link being secured to an arm 33^a, of a crank member 33 mounted on the frame 14 for rocking on a pivot shaft 34 journaled in bearing lugs 35 of said frame. Said crank member 33 has a projecting cam traveler 36^b for riding on a fixed cam 36 which is formed on an extended end of a bracket 37 rigidly secured on the base 11 by bolts 37^a adjacent the stanchions 12, as shown in Figs. 1 and 2.

The traveler 36^b is retained against said cam 36 through the action of a tension spring 38 which has one end 38^a anchored to a rearwardly extending portion 30^a of slideway 30, and the other end 38^b secured to the cross-head 29.

The operation of the means for automatically rotating the discs as a unit from the type letter setting position to their effective position for contacting with the material M will now be apparent. On depressing the handle 19 the frame 14 is swung downwardly and the cam traveler 36^b, riding on the cam 36, rocks the crank member 33 on the shaft 34 and moves the link 32, pin 28, and cross-head 29 forward against the action of the spring 38. The pin 28, being in engagement with the plate 27, rotates the interconnected discs as a unit on the shaft 18. Preferably 20 the cam guide 36 is designed to complete the rotary motion given the discs before the frame 14 reaches its lowermost position, so that the discs are relatively stationary with respect to the frame just before and 25 during the time the type letters contact with the article or material M.

Upon releasing the handle 19, the frame will automatically return to its raised position through the action of spring 16, and the 30 tension spring 38 will retract the cross-head 29 and return the discs to their normal position for setting.

Where ordinary or plain printing is to be done by the apparatus 10, a suitable form 35 of ink applying device (not shown) may be used to ink the type elements in any manner well understood in the art. Such device is preferably installed just below the handle 19 so that the type elements are inked as the discs are revolved on the shaft 18 during the lowering movement of the frame 14, as described above.

So that the apparatus 10 may be used for branding, embossing, or applying lustrous 45 letters, a suitable heating means for the type elements is provided. Said means may comprise an electric heater coil 40 of any suitable construction embedded in a channelled annular holder 41 suitably insulated and 50 mounted on the disc C adjacent the peripheral surface thereof, as shown in Figs. 4 and 5. Concentrically disposed slip rings 42 supported on an insulating member 43, are mounted to turn with said disc C, and suitable brushes 44 for connecting the heater coil 40 to ends 46^b of the conductor wires 46 are supported on an insulating member 45, which, in turn, is rigidly mounted on the shaft 18. Said member 45 also serves as a collar to prevent side displacement of disc C along shaft 18.

The conductor wires 46 may be arranged to pass through a central passage 18^a in the shaft 18 and may be disposed in a channel 65 groove 14^a extending along the frame 14.

The ends 46^b of said conductor wires may extend through an axial opening 15^a provided in the shaft 15 and may be terminated by a receptacle 47^a of a detachable fitting having a cap 47^b adapted to be connected with a 70 suitable electric power source (not shown) by means of a portable conductor 48.

The discs C, R and L are preferably made of copper, bronze, brass, aluminum or other material having a relatively high heat conductivity so that the discs R and L are readily heated to the required working temperature by contact with the disc C. 75

In branding or plain embossing an article, or material M, the coil 40 is first connected to 80 the power source for heating the type letters which, after having been set, are forced against the article or material M by applying pressure on the handle 19.

By interposing a metallic foil or leaf of 85 gold, silver, aluminum, or other metal, or composition between the heated type letters and the article or material M, lustrous letters may be stamped or printed on the latter. For automatically feeding such foil in proper 90 operating sequence, a strip feeding mechanism F may be incorporated in the apparatus, 10. In the form shown in the drawing, said mechanism comprises a pair of spools 50 and 51 revolvably mounted on shafts 52 and 53 95 respectively, which are suitably supported from the frame bracing members 14^a. A supply of strip material 54 is carried on spool 50. Said strip material has one side thereof coated with a metallic foil, (not shown) from 100 which the lustrous letters are formed, and is fed between the type elements and the platen 13 with the coated side facing down. Any suitable strip material or metal foil such as 105 is in commercial use may be employed.

Stretcher spacers 55 and 56 are mounted on the coiled ends 57^a and 58^a of spring arms 57 and 58 respectively, the latter being supported on the shafts 52 and 53. Said stretcher spacers are adapted to guide the strip material 54 across the discs and to hold it out of contact therewith when the frame 14 is in raised position, as shown in Fig. 4^a.

Coupled to spool shaft 52 through a universal joint 60 is a drive shaft 61 journaled 115 in a bearing 62 of a hanger 63. Said shaft 61 has secured thereto a pair of oppositely set ratchet wheels 64 and 65 and has loosely mounted on the free end thereof a pinion 66, the latter engaging with a fixed arcuate rack 120 67 secured to one of the stanchions 12. Pawls 68 and 69 co-operate with the ratchet wheels 64 and 65 respectively, pawl 68 being mounted on the hanger 63, and pawl 69 being carried by the pinion 66. As seen from Fig. 3, 125 the feeding mechanism F will be effective to advance the strip material 54 only on the return motion of the frame 14 to its raised position, when the pawl 69 and ratchet wheel 65 will interlock with the pinion, while on down- 130

ward travel of said frame, the pawl 68 will retain the wheel 64 against reverse rotation while the pawl 69 slips over the wheel 65, as will be readily understood.

In using the invention, the portable conductor 48 is connected to an electric power source to heat the type elements on the discs. By manipulating the knobs 25R, 25L as described above, the discs are set so that the desired combination of letters or other devices of the type elements appear at V. A brief case or other article M is then positioned on the platen 13 and the handle 19 depressed, thus causing the discs to be rotated as a unit to the printing position, that is, facing the platen 13. As the frame 14 descends, the type elements engage the strip material 54 to press the foil or coated side thereof against the material M. The heat from the type elements causes the foil to adhere to the material in outline to correspond to the shape or design of the type or other characters on the type elements.

In Figs. 6, 8, 9, and 10 are shown various means of providing a type border design. In the simplest form (see Fig. 10) the type letters 70 have surrounding border portions 71 formed integral therewith, said portions being constructed so as to align with similar border portions of the type elements on the adjacent disc so as to form a substantially continuous border when the type letters are set up.

In Fig. 6 (see also Figs. 4 and 4^a) the type border 80^a is formed on a separate member 80 which is supported by the stretcher spacers 55 and 56 on links 81. Said member 80 is provided with a central opening 80^b through which the type elements 20 are adapted to project to align with said border 80^a. To assure perfect alignment the upper side of the rim portion of said opening 80^b is made with a bevelled seat 80^c for receiving the chamfered outer edges 82 of the discs R and L. As seen from Fig. 4^a, the links 81 normally hold the member 80 spaced from the discs C, R and L and, the strip material 54, and on the downward movement of the frame 14, said discs first engage with the member 80, aligning the border 80^a with the type elements which thereafter are applied in unison to the material M. By making member 80 of relatively good heat conducting material, it will transmit heat, while in contact with the discs C, R and L, to the border 80^a and will form a lustrous border design on the article or material M, simultaneously with the application of the letters from the type elements.

Referring now to Figs. 8 and 9, the type border 90^a here shown is formed on a member 90 which is adapted to be detachably mounted on the discs C, R and L, said member being provided with a central opening 90^b through which the type elements 20 project

for alignment with the border 90^a when said member is mounted in position on the discs. The frame handle 99 is constructed with a plunger 91 extending axially therethrough, said plunger having a control knob 92 at the outer end thereof and a bifurcated portion 93 attached at the inner end, the portion 93 being adapted to be reciprocated by the plunger over the cross bar 14^c. A suitable compression spring 94 is provided between the handle 99 and the knob 92 for normally retaining the plunger 91 and the bifurcated portion 93 in retracted position. The portion 93 may have a pair of inwardly extending, aligned pins 93^a adapted to engage in side slots 90^c 80 of said member 90.

To hold the member 90 against accidental displacement when mounted on the discs, spaced lug portions 90^d are provided on said member, said portions 90^d being constructed 85 to receive the rim portions of the discs C, R and L between them and to house a suitable spring detent, such as the spring pressed balls 95, which are adapted to set in suitable spherical depressions 96, provided in the outer sides 90 of the edge portions of discs R and L. Radial track grooves 97 extending outwardly from said depressions may be provided to facilitate the mounting and dismounting of the member 90. The operation of applying the border 95 member 90 in position on the discs is as follows: With the plunger 91 in retracted position, the member 90 is mounted over the cross bar 14^d with the pin 93^a in the slots 90^c. After the type elements 20 have been set in the desired sequence at V, the plunger knob 92 is pushed in, causing the member 90 to move toward the discs, the balls 95 entering the grooves 97. When the member 90 is all the way in, the balls 95 seat themselves in the depression 96 and the handle 99 is then depressed to imprint the article or material M.

It will be noted that the pins 93^a leave the slots 90^c when the member 90 rotates with the discs and re-enter the said slots on the return of the frame 14 and discs to their normal raised positions. On releasing the knob 92, the plunger is retracted, and disengages and carries the member 90 with it, so that the discs are left free to permit changing the setting of the type elements 20.

As has been described above, grooved spaces c, r, and l may be provided in the periphery of the discs C, R and L respectively for receiving an interchangeable type element 20^a. To this end, the grooved spaces c, r, and l are aligned at V in the usual manner by setting the discs, then the element 20^a is slipped in place to engage in said aligned space which may be of dove-tail construction to firmly interlock said element 20^a to the discs. The insignia, symbols, or legend on the face side of the type element 20^a may be applied to an article or material M, by depressing the handle 19 as has already been described above.

By making the element 20^a of material of relative high heat conductivity, it will become heated by contact with the discs and will be effective to produce the lustrous form of impressions.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described our invention, we claim as new and desire to secure by Letters Patent:

1. An apparatus of the character described comprising a plurality of type elements mounted for movement relative to each other, means for rotating and sliding all but one of said elements with respect to the other elements for selectively aligning same, means to support an article, and means for bringing the type elements and article into contact.

2. In an apparatus of the character described, a plurality of discs parallelly mounted for movement relative to each other, type elements carried on the peripheral surface of each disc, and means to slide all but one disc for releasably interlocking said discs with said elements aligned in a desired sequence.

3. In an apparatus of the character described, a plurality of discs parallelly mounted for movement relative to each other, type elements carried on the peripheral surface of each disc, means for selectively aligning said elements, and means for releasably interlocking said discs with said elements, some of said discs being slidably mounted, at least one of said discs being non-slidably mounted in aligned position.

4. In an apparatus of the character described, a plurality of discs parallelly mounted for movement relative to each other, type elements carried on the peripheral surface of each disc, a border type member releasably engaging said discs for outlining said elements, said border member normally being spaced from said discs and means for releasably interlocking said discs with said outlined elements aligned in a desired sequence.

5. In an apparatus of the character described, a plurality of discs parallelly mounted for movement relative to each other, type elements carried on the peripheral surface of each disc, means for selectively aligning said elements, means for releasably interlocking said discs with said elements releasably engaging said discs in alignment, a border type member for outlining said ele-

ments, said border member normally being spaced from said discs and means for actuating the outlined elements as a unit.

6. In an apparatus of the character described, a plurality of discs parallelly mounted for movement relative to each other, type elements carried on the peripheral surface of each disc, means for releasably interlocking said discs with said elements aligned in a desired sequence, some of said discs being slidably mounted, at least one of said discs being non-slidably mounted and means carried by said discs for heating said elements.

7. In an apparatus of the character described, a plurality of discs parallelly mounted for movement relative to each other, type elements carried on the peripheral surface of each disc, a border type member for outlining said elements, means for releasably interlocking said discs with said outlined elements aligned in a desired sequence, and means carried by said discs for heating said elements and border member.

8. In an apparatus of the character described, a plurality of discs parallelly mounted for movement relative to each other, type elements carried on the peripheral surface of each disc, means for selectively aligning said elements, means for releasably interlocking said discs with said elements in alignment, a border type member for outlining said elements, means carried by said discs for heating said elements and border member and means for actuating the outlined elements and heater means as a unit.

9. In an apparatus of the character described, a plurality of discs parallelly mounted for movement relative to each other, type elements carried on the peripheral surface of each disc, a border type member for outlining said elements, normally spaced from said discs, means for releasably interlocking said discs with said outlined elements aligned in a desired sequence, said border type being movable into alignment with said type elements, and means for feeding a strip in spaced relation with respect to the aligned border member and type outlined elements, as and for the purpose described and specified.

10. In an apparatus of the character described, a plurality of discs parallelly mounted for movement relative to each other, type elements carried on the peripheral surface of each disc, means for releasably interlocking said discs with said elements aligned in a desired sequence, means carried by said discs for heating said elements, and means for feeding a strip over the said heated aligned elements.

11. In an apparatus of the character described, a plurality of discs parallelly mounted for movement relative to each other, type elements carried on the peripheral surface of each disc, a border type member for outlining said elements, means for releasably interlocking said discs with said outlined ele-

- ments aligned in a desired sequence, means carried by said discs for heating said elements and border member, and means for feeding a strip over the said heated outlined elements.
5. 12. In an apparatus of the character described, a plurality of discs parallelly mounted for movement relative to each other, type elements carried on the peripheral surface of each disc, means for selectively aligning said elements, means for releasably interlocking said discs with said elements in alignment, a border type member for outlining said elements, means carried by said discs for heating said elements and border member,
10. 15. means for feeding a strip over the heated outlined elements, and means for actuating the heated outlined elements and strip feeding means as a unit.
20. 13. An apparatus of the character described comprising a shaft, a plurality of discs mounted thereon for rotation relative to each other, and type elements carried on the peripheral surface of each disc, some of said discs being slidably mounted along said shaft and at least one disc non-slidably mounted on said shaft for releasably interlocking with said slidable discs for aligning said elements in a desired sequence.
25. 14. An apparatus of the character described comprising a shaft, a plurality of discs mounted thereon for rotation relative to each other, and type elements carried on the peripheral surface of each disc, and means for slidably moving all but one of said discs along the shaft for releasably interlocking the discs with said elements aligned in a desired sequence.
30. 15. An apparatus of the character described comprising a shaft, a plurality of discs mounted thereon for rotation relative to each other, and type elements carried on the peripheral surface of each disc, at least one of said discs being slidably mounted on said shaft for releasably interlocking said discs with said elements aligned in a desired sequence, and means for heating said elements movably mounted with said discs.
35. 16. An apparatus of the character described comprising a shaft, a plurality of discs mounted thereon for rotation relative to each other, and type elements carried on the peripheral surface of each disc, at least one of said discs being slidably mounted on said shaft for releasably interlocking said discs with said elements aligned in a desired sequence, and a coil for heating said elements carried by one of said discs.
40. 17. An apparatus of the character described comprising a shaft, a plurality of discs mounted thereon for rotation relative to each other, and type elements carried on the peripheral surface of each disc, and means for slidably moving all but one of said discs along the shaft for releasably interlocking the discs with said elements aligned in a desired sequence, and a heater coil carried by the non-slidably disc.
45. 18. An apparatus of the character described comprising a shaft, a plurality of discs mounted thereon for rotation relative to each other, and type elements carried on the peripheral surface of each disc, some of said discs being slidably mounted along said shaft and one disc non-slidably mounted on said shaft for releasably interlocking with said slidable discs for aligning said elements in a desired sequence, and a coil carried by said non-slidably mounted disc for heating said elements.
50. 19. In an apparatus of the character described, a plurality of discs parallelly mounted for movement relative to each other, type elements carried on the peripheral surface of each disc, said discs having at least one grooved space between said type elements, and means for releasably interlocking said discs with said elements and grooved spaces aligned in a desired sequence.
55. 20. In an apparatus of the character described, a plurality of discs parallelly mounted for movement relative to each other, type elements carried on the peripheral surface of each disc, said discs having at least one grooved space between said type elements.
60. 21. In an apparatus of the character described, a plurality of discs parallelly mounted for movement relative to each other, type elements carried on the peripheral surface of each disc, a demountable type element, each disc having at least one grooved space between said type element for receiving said demountable type elements, and means for setting the discs with said elements and grooved spaces aligned in a desired sequence.
65. 22. In an apparatus of the character described, a plurality of discs parallelly mounted for movement relative to each other, type elements carried on the peripheral surface of each disc, a demountable type element, each disc having at least one grooved space between said type element, means for selectively aligning said elements and grooved spaces, and means for interlocking said discs with said groove spaces aligned for receiving said demountable type element.
70. 23. An apparatus of the character described comprising a plurality of discs, spaced type elements carried on the peripheral surfaces of said discs, a demountable type element, each disc having at least one grooved space between said spaced type elements for receiving said demountable type element, means for selectively aligning said elements on the discs, means adapted to support an article and means for bringing the aligned elements and article in contact.
75. 24. An apparatus of the character described comprising a plurality of discs, spaced type elements carried on the peripheral surfaces of said discs, a demountable type element,

- each disc having at least one grooved space between said spaced type elements for receiving said demountable type element, means for selectively aligning said elements on the discs, and means for heating said elements. 5
25. An apparatus of the character described comprising a plurality of discs, spaced type elements carried on the peripheral surfaces of said discs, a demountable type element, 10 each disc having at least one grooved space between said spaced type elements for receiving said demountable type element, means for selectively aligning said elements on the discs, a border type member for outlining said 15 elements, means spaced from the outline elements adapted to support an article, and means for bringing the outlined elements and article in contact as and for the purpose described and specified. 20
26. An apparatus of the character described comprising a plurality of discs, spaced type elements carried on the peripheral surfaces of said discs, a demountable type element, each disc having at least one grooved space 25 between said spaced type elements for receiving said demountable type elements, means for selectively aligning said elements on the discs, a border type member for outlining said elements, means spaced from the 30 outlined elements adapted to support an article, means for interposing a foil between the outlined elements and the article, and means for bringing the outlined elements, foil, and article in contact, as and for the purpose described and specified. 35
27. An apparatus of the character described comprising a plurality of discs, spaced type elements carried on the peripheral surfaces of said discs, a demountable type element, 40 each disc having at least one grooved space between said spaced type elements for receiving said demountable type elements, means for selectively aligning said elements on the discs, a border type member for out- 45 lining said elements, means spaced from the outlined elements adapted to support an article, means for interposing a foil between the outlined elements and the article, means for heating the outlined elements and means 50 for bringing the heated outlined elements, foil and article in contact as and for the purpose described and specified. 55
28. In an apparatus of the character described comprising a plurality of type elements mounted for movement relative to each other, means for selectively aligning said elements in unobstructed view of the operator, means spaced from the elements adapted to support an article, and means for bringing the type elements and article in contact, as and for the purpose described and specified. 60
29. In a marking apparatus of the character described, a platen adapted to support an article to be marked, type elements rotatably mounted in spaced relation to the platen, electric means for heating said elements, means for feeding a strip coated with a metallic substance between the platen and type elements, and means for bringing the disc 65 and heated type elements against the strip for contacting with the article. 70
30. In a marking apparatus of the character described, a platen adapted to support an article to be marked, a disc rotatably mounted and normally positioned in spaced relation to said platen, type elements mounted on the disc, an electric heating means carried by the disc heating said elements, means for feeding a strip coated with a metallic sub- 75 stance between the platen and type elements, and means for bringing the disc and heated type elements against the strip for contacting the article. 80
31. In a printing machine, a support, a plurality of type wheels mounted on said support, means for positioning said wheels so that a desired combination appears at a predetermined position, and means for moving said support to printing position and simultaneously moving said combination to be positioned for making a desired imprint when said support reaches the printing position. 85
32. In a printing machine, a support, a plurality of type wheels mounted on said support, means for positioning said wheels so that a desired combination appears at a predetermined position, and means for moving said support to printing position and simultaneously moving said combination to be positioned for making a desired imprint when said support reaches the printing position, and means for simultaneously returning said support and said combination to their initial 90 positions. 100
33. In combination, a plurality of wheels having a plurality of separated type elements on the periphery thereof, means for setting up said elements in any desired sequence, means for making a border imprint in relation to said type element, said border means being normally spaced from said type elements, means for moving said set up type elements into printing position, said border 105 means contacting with said type elements before said elements contact the part to be imprinted, and then movable simultaneously with said elements to imprinting position. 110
- In testimony whereof we affix our signatures. 120
